DOOR OPERATING MECHANISM

Edward S. Pringle, Norfolk, Va., assignor to The
 J. G. Wilson Corporation, New York, N. Y., a
 corporation of Virginia

Application January 30, 1945, Serial No. 575,269

3 Claims. (Cl. 268—59)

1

This invention relates to door operating mechanism, and more particularly concerns improved mechanism for raising and lowering a vertically movable sectional door of the type commonly used for residential garages and like building entrances.

In the past, vertically movable doors of the type described have been generally designed for manual operation. They are usually provided with counter-weights or springs which act against the pull of gravity on the door structure and so assist in lifting the door to its open position. Despite such counter-weighting, the opening and closing of a door of this nature requires the exertion of considerable force and is generally a laborious operation.

In accordance with the present invention, it is proposed to provide a compact and simplified power-operated mechanism for raising and lowering a door upon manipulation of a simple control means, and to so construct and arrange the operating mechanism that the door is opened by energy stored in a spring or its equivalent and is lowered by a motor that charges or winds up the spring while the door is being lowered by gravity to its closed position. The invention further contemplates the provision of improved control means for the door operating mechanism including a movable element in the nature of a spring latch for securing the door in its lowered closed position and a switch for controlling the energization and de-energization of the motor. A lock may be provided in conjunction with the control means, whereby the door may be operated from outside the building by a key. The arrangement is preferably such that the switch and latch are operatively associated so that the switch can be closed to energize the motor and so close the door when the door is in any position other than its closed and latched position, and that the movement of the latch incident to closing and latching the door moves the switch to its open or motor de-energizing position. The invention further contemplates the provision of a combined switch and latching mechanism which is simple in construction and easy to operate and which requires a minimum amount of wiring for its connection with the motor. Various other objects, advantages and characteristic features of the invention will be apparent from the ensuing description of an embodiment thereof.

In accordance with the invention, the motor operates only during movement of the door to the closed position. This arrangement permits the use of a small, compact and simple irreversible

2

motor of the high torque and low speed type, and the motor may be directly connected to the door drive without the use of speed reduction gearing. The arrangement is extremely compact and provides a door operating mechanism which is easy to manufacture, test, install and operate.

In describing the invention in detail, reference will be made to the accompanying drawing in which a typical embodiment thereof has been 10 illustrated. In the drawings:

Fig. 1 is a perspective view showing an installation of mechanism embodying the invention in connection with a vertically movable door;

Fig. 2 is an elevation, partly in section, of the 15 motor and cable drum assembly of the apparatus shown in Fig. 1;

Fig. 3 is an enlarged elevation of the latch and switch mechanism of the apparatus;

Fig. 4 is a horizontal section taken along the 20 line IV—IV of Fig. 3 and viewed in the direction of the arrows;

Fig. 5 is a vertical section taken along the line 25 V—V of Fig. 4 and viewed in the direction of the arrows, showing the parts in the latched or door securing position;

Fig. 6 is a vertical section as in Fig. 5 showing the parts in the unlatched or door releasing position; and

Fig. 7 is a vertical section as in Figs. 5 and 6 30 showing the parts and the position they assume when the door has moved away from its latched position and is in an open position.

In summary, the disclosed embodiment of the invention includes a vertically movable door suitably connected to a biasing means in the form of a spring driven drum, the spring of which is normally wound up or charged to a tension sufficient to move the door upward from any position to its fully open position against the action of gravity. A motor is connected to the spring driven drum and acts when energized to rotate the drum in a direction to rewind or charge the spring, thereby permitting the door to move downward by gravity from any position to its fully closed position. A latch is arranged to secure the door in its fully closed position against the pull of the spring, and a switch is associated with the latch and is operable to permit energization of the motor and closure of the door when the door is in any position except its fully closed and latched position. The latch and switch are so interconnected that movement of the latch incident to closing and securing the door opens the switch and so de-energizes the motor.

Referring more specifically to the drawings, a

sectional vertically movable door 1 of conventional construction is shown mounted and guided by rollers 2 running in guide tracks 3. The tracks 3 extend vertically along the opposite sides of the door opening and run back horizontally along the ceiling of the building, and the door moves from the closed position shown upward vertically and rearward substantially horizontally to its open position. Cables 4 are secured to opposite sides of the bottom section of the door 1 and are disposed to be wound on a rotary drum 5 to which the cable ends are secured by suitable means such as the set screws 6.

The drum 5 is mounted on and fixed to a rotary tube 7, one end of which is mounted on the post 9 of a fixed wall bracket 10 by means of a bearing 8. The opposite end of the tube is fixed to the shaft 12 of an electric motor 13 by a plug 11, and the motor is suitably secured to the ceiling or any other support as illustrated in Fig. 1. A coiled torsion spring 14 is enclosed in the tube 7 with its opposite ends respectively fixed to the fixed post 9 and the plug 11 which is secured to the tube 7 and to the motor shaft 12.

The spring 14 is wound up or charged to a tension such that through rotation of the tube 7 and drum 5 it will lift the door upward from any position to its fully open position. This condition is generally met by designing and tensioning the spring 14 to exert a lifting force about 5% to 15% greater than the effective weight of the door at any point.

The motor 13 is preferably of the high torque low speed type, and is not reversible. It runs when energized in a direction to rewind or charge the spring 14 and so to unwind the cables 4 from the drum 5 whereby the door 1 is permitted to move downward by gravity. The spring 14 counterbalances the effective weight of the door and exerts an additional force which biases the door to move upwardly, and the motor need exert only sufficient torque to overcome the force by which the effective spring force exceeds the effective door weight. For this reason, the motor may be of low power and small size, and no speed reduction or torque multiplying mechanism need be interposed between the motor and the door operating drum.

The energization of the motor 13 and the securing and releasing of the door is controlled by a combined latch and switch mechanism. This mechanism includes a base 15 suitably mounted on the inside of the building wall adjacent the door and carrying a latch 16 pivotally secured thereto at 17. A cover 18 secured to the base 15 encloses the latch but permits movement thereof laterally of the base as shown in Figs. 3, 5, 6 and 7. A shaft 19 is journaled in the base 15 and cover 18 and carries an operating handle 21 fixed thereto outside the cover 18 as shown in Figs. 3 and 4. A cam 20 is fixed to the shaft 19 inside the cover 18, and a mercury switch 22 is mounted on the cam 20. The switch 22 is of conventional construction and is so mounted that its contacts which are at the right hand end of the switch tube, are open when the cam 19 is in positions where the cam point slants to the left of the vertical, and are closed when the cam point slants to the right of the vertical as shown in Figs. 5, 6 and 7. A leaf spring 23 is suitably mounted on the base 15 to bias the latch 16 to move outward toward its door securing position shown in Fig. 6.

The door 1 has fixed thereto a locking bar 24 located at a suitable height and bent to pass

around the track 3 so that its end is disposed for engagement by the latch 16 when the door is closed (Figs. 3 and 4).

The latch and switch mechanism is normally located inside the building and provision is preferably made for operating the shaft 19 of the mechanism from outside the building. As shown in Fig. 4, a cylinder lock 25 of known construction operable by a key 26 may be mounted at the outer end of an opening through the building wall, and the stem 27 of the lock may be suitably secured to the shaft 19 through a connection providing sufficient lost motion to permit the return of the key 26 to a point where it can be removed from the lock when the door is in a position where such removal is desired.

The latch 16 has a tapered hook portion 16' arranged to engage and move over the upper edge of the bar 24 when the door is in its fully closed position. The under surface of the hook 16' which engages the bar 24 slants inward and upward but forms an angle of not less than 90° with a line from the axis of the pivot 17 to the point of latch engagement. There is thus a tendency for the bar 24 to be drawn against the edge of the base 15 and cover 18 as an aid to the detaining action of the hook 16'.

The cam opening 30 in the latch 16 has two oppositely disposed cam engaging surfaces 16'' and 30' therein. When the latch 16 is in the door securing position as shown in Fig. 5, the surface 30' is so disposed with relation to the cam 20 that the cam cannot be turned clockwise far enough to slant to the right of a vertical position, and accordingly the contacts of the mercury switch 22 cannot be closed. Rotation of the shaft 19 counter-clockwise as viewed in Figs. 5 and 6 causes the cam 19 to engage the surface 16'' and so turn the latch 16 to its retracted or door releasing position against the bias of the spring 23, as shown in Fig. 6. The contacts of the switch 22 obviously remain open during this counter-clockwise rotation of the shaft 19.

Movement of the latch 16 in a direction to retract the hook 16' from the bar 24 is facilitated by the fact that the hook moves upwardly from its fully engaged position and tends in such movement to force the bar 24 into close frictional engagement with the edge of the base 15 and cover 18. Such frictional engagement partly resists or retards the upward movement of the door as the hook is being retracted, and so prevents undue frictional resistance to the retracting movement of the hook.

After the door has moved up from its closed position, the latch 16 may be moved to an extreme extended position as shown in Fig. 7. This movement may be caused by the spring 23, or this spring may be so designed that it does not move the latch beyond the securing position of Fig. 5, and clockwise rotation of the shaft 19 to a position in which the cam 20 slants slightly to the right of the vertical, as shown in broken lines in Fig. 7, may move the latch to the extreme position of Fig. 7. With the latch in the extreme position, the contacts of the switch 22 can be closed since the cam 20 can be tilted to the right of a vertical position into engagement with the surface 30'. The closed position of the switch 22 is shown in broken lines in Fig. 7.

When the door 1 moves to its closed position, the bar 24 engages the hook 16' of the latch 16 and first swings the latch back to its retracted

position as shown in Fig. 6 and then permits movement of the latch out to the door securing position as shown in Fig. 5. As the latch 16 moves from the position of Fig. 7 to that of Fig. 6, the cam 20 is engaged and turned counter-clockwise by the surface 30' to a position in which the cam point slants to the left of the vertical, as shown in Fig. 6, thereby opening the contacts of the switch 22.

The contacts of the switch 22 are connected in series with an energizing circuit for the motor 13, and this circuit includes the cable 28 connected to an electrical outlet and the cable 29 which connects one of the leads of the cable 28 in series with the switch contacts and back to the motor 13.

In operation, the door 1 is opened by retracting the latch 16 through counter-clockwise rotation of the shaft 19 as described above, whereupon the door is lifted by the spring 14 which rotates the tube 5 and drum 6 and so pulls the door upward through the cables 4. This rotation of the tube 7 by the spring 14 turns the motor 13 in a reversed direction, the motor being de-energized, and this motor rotation stabilizes and slightly retards the motion of the door. If desired, the door may be lowered from any intermediate position by turning the shaft 19 clockwise and so closing the contacts of the switch 22 as explained above, the latch 16 being in or movable to its extreme extended position as shown in Fig. 7 during the upward travel of the door.

When the switch 22 is closed with the door 1 fully opened or at any intermediate position, the motor 13 is energized and turns the tube 7 in a direction to lower the door, the spring 14 being wound up or charged as the door is lowered. By turning the shaft 19 counter-clockwise and so opening the switch contacts, the door may be raised from any intermediate point. As the door moves to its fully closed position, the bar 24 pushes the latch 16 back to its retracted position and so opens the contacts of the switch 22 as explained above, thereby de-energizing the motor 13. The momentum of the door 1, the motor 13 and the connected parts is sufficient to insure complete closing of the door and movement of the bar 24 to a point where it is latched under the hook 16'. With the door in its fully closed and latched position, the shaft 19 is held against clockwise rotation to a position to close the switch 22. This prevents accidental energization of the motor 13 when the door is latched shut. Burning out or other injury of the motor by energization thereof with a locked load thereon is thus prevented.

In case of failure of the power supply of the motor, the door can be readily opened and closed by hand, opening movement of the door being effected by the spring 14 in the manner described above.

Counter-balancing weights might be substituted for the spring 14. The use of a spring is generally preferred, particularly because it results in a compact and unitary structure and permits factory assembling and testing as well as installation. The improved operating mechanism of the invention may be readily installed on doors which have been manually operated, such installation involving only the making of the desired connections and the removal of such counter-balancing mechanism as may have been originally provided. The invention which is defined in the appended claims is not limited to

the structural details of the specific embodiment thereof herein described.

I claim:

1. Door operating mechanism of the character described comprising, in combination, a door movable between an upper open position and a lower closed position, a cylindrical tube rotatably secured to a fixed support adjacent the top of said door when in its closed position, at least one flexible cable connected between a point adjacent the lower edge of the door and said tube and adapted to be wound on said tube to lift said door when said tube rotates, a coiled torsion spring enclosed within said tube and connected between said fixed support and said tube, said spring being of sufficient strength as to apply sufficient torque to said tube as it unwinds to rotate said tube to move the door to its open upper position, and an electric motor directly connected to said tube and acting when energized to rotate said tube in a direction only to wind up said spring and to unwind said cable from said tube to permit said door to move to its lower closed position by gravity.
2. A door securing and controlling mechanism for vertically movable power operated doors comprising in combination with a vertically movable door, a stationary latch adjacent said door movable between a retracted position and a door securing position, a spring biasing said latch to move from its retracted position toward its door securing position, a catch on said door engageable by said latch and disposed to move said latch to its retracted position as the door is moved toward its lower closed position and to permit said latch to move to its door securing position when said door is closed, a switch movable between a circuit closing position and a circuit opening position, a part of said latch being disposed to engage said switch and move the same to its circuit opening position when said latch is moved to its retracted position and a second part on said latch being disposed to prevent movement of said switch to its circuit closing position when said latch is in its door securing position.
3. A door securing and controlling mechanism for a vertically movable power operated door comprising in combination with a vertically movable door, a stationary latch adjacent the path of said door movable between a retracted position, an intermediate door securing position and an extended position, a spring biasing said latch to move from its retracted position toward its intermediate and extended positions, a catch on the door engageable by said latch and disposed to move said latch to its retracted position as the door is moved toward its lower closed position, to permit said latch to move to its intermediate door securing position when said door is closed and to permit said latch to move to its extended position when said door is open, a switch movable between a circuit closing position and a circuit opening position, a part on said latch being disposed to engage said switch and move the same to its circuit opening position when said latch is moved to its retracted position, a second part on said latch being disposed to prevent movement of said switch to its circuit closing position when said latch is in its intermediate door securing position, said second part on said latch acting when said latch moves to its extended position to permit movement of said switch to its circuit closing position, and man-

ually operable means for moving said switch under the control of said latch parts.

EDWARD S. PRINGLE.
